MAGNETIC CAN OPENER

Harry Glovinsky, Utica, N. Y.

Application March 20, 1950, Serial No. 150,786

6 Claims. (Cl. 30—22)

1

The present invention relates to new and useful improvements in can openers and more particularly to a magnet attached to the can opener to attract and hold metal splinters caused by the action of opening a can and to prevent the splinters or metal particles from falling into the contents of the can.

An important object of invention is to provide means for holding a permanent magnet on the back of a can opener and with the ends of the magnet positioned at opposite sides of the cutter of the opener and held in close proximity to the can to attract and hold metal particles which might be broken off during the can opening operation.

A still further object is to provide spring means exerting tension on the magnet to provide a forward and backward rocking movement thereof on the can opener at its cutting edge to maintain the magnet in close proximity to the top of the can during the rocking movement of the can opener in its cutting action.

A still further object is to provide a magnet which is adaptable to a can opener without necessitating any changes or alterations in the construction thereof and embodying simple and practical attaching means for the magnet to insure its efficient operation.

A still further object is to provide an attachment of this character which is relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view;

Figure 2 is a fragmentary top plan view;

Figure 3 is an enlarged transverse sectional view taken on a line 3—3 of Figure 1;

Figure 4 is a perspective view of the housing or cover for the magnet;

Figure 5 is a bottom plan view thereof;

Figure 6 is a perspective view of the slide for the magnet, and;

Figure 7 is a perspective view of the magnet with the cover or housing thereon.

Referring now to the drawings in detail wherein for the purpose of illustration I have disclosed a preferred embodiment of the invention, the numeral 5 designates the can opener generally and which is of a conventional type including a

2

handle 6, a shank 7 of strap metal construction, a cutter 8, a forwardly projecting guide 9 and front and rear metal loops 10 and 11 rising from the back of the shank at its front end and constructed in the usual manner to provide a jar cap prying or removing tool. All of the elements referred to above form part of the usual type of can opener.

The present invention comprises a hollow slide 12 mounted on shank 7 and behind which is positioned a coil spring 13 with the rear end of the spring abutting the front end of handle 6 and with the front end of the spring abutting the rear end of slide 12. Slide 12 is formed at its front end with a pair of forwardly extending diverging arms 14 having inwardly extending shoulders 15 at the front ends of the arms and terminating at the inner ends of the shoulder in forwardly projecting lugs 16 and with the lugs 15 of the pair of arms 14 opposed to each other and positioned at opposite sides of the shank 7 above cutter 8. The upper edge of slide 12 is formed with a forwardly projecting arm 17.

A horseshoe type permanent magnet 18 is mounted in a straddling position on the upper edge of shank 7 between front and rear loops 10 and 11 and with the lugs 16 positioned against the inner edges of sides or legs of the magnet and with shoulders 15 bearing against the rear of the magnet.

The top of the magnet is enclosed in a cover or housing 19 having an insulation and cushioning lining 20 and a pin or stem 21 rises from the top of cover 19 and which projects through a metal strap or tie 22 having its front end inserted through front loop 10 and formed with a clip or hook 23 engaging the front edge of the front loop to hold the strap therein and having the rear end of the strap 22 inserted through the rear loop 11 and also formed with a clip or hook 24 engaging the rear edge of loop 11 to hold the strap therein. The front end of arm 17 of slide 12 projects through rear loop 11 to abut the rear side of the housing 19 for the magnet.

In the operation of the device, magnet 18 is placed over shank 7 for rocking movement thereon between front and rear loops 10 and 11 of the can opener, the magnet being held in position by metal strap or tie 22 anchored to the loops, spring 13 forces slide 12 forwardly to hold shoulders 15 and upper arm 17 against the rear side of the magnet.

As the cutter 8 cuts the top of a can the lower ends of magnet 18 ride along the can at opposite sides of the cutter to attract and hold loose

particles of metal and during the rocking motion of the can opener in its progressive cutting action magnet 13 engages the can and is forced rearwardly on shank 7 against the tension of spring 13 which then returns the magnet forwardly to always hold the magnet closely at the point at which the can is being cut.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A magnetic attachment for can openers comprising the combination of a tool shank having a cutter at its front end, a permanent horseshoe type magnet rockably supported in a straddling position on the shank with its ends positioned at opposite sides of the cutter and movable rearwardly by contact of the magnet with a can during actuation of the cutter, and spring means holding the magnet in a forward position.

2. A magnetic attachment for can openers comprising the combination of a tool shank having a cutter at its front end, a permanent horseshoe type magnet rockably supported in a straddling position on the shank with its ends positioned at opposite sides of the cutter and movable rearwardly by contact of the magnet with a can during actuation of the cutter, a slide on the shank behind the magnet, and spring means holding the slide forwardly against the magnet to return the magnet to a forward position.

3. A magnetic attachment for can openers comprising the combination of a tool shank having a cutter at its front end, a permanent horseshoe type magnet rockably supported in a straddling position on the shank with its ends positioned at opposite sides of the cutter and movable rearwardly by contact of the magnet with a can during actuation of the cutter, means holding the magnet on the shank, a slide on the shank behind the magnet, and spring means

holding the slide against the rear of the magnet to return the magnet to a forward position.

4. A magnetic attachment for can openers comprising the combination of a tool shank having a cutter at its front end, a permanent horseshoe type magnet rockably supported in a straddling position on the shank with its ends positioned at opposite sides of the cutter and movable rearwardly by contact of the magnet with a can during actuation of the cutter, a metal strap anchored at its ends to the can opener and holding the magnet on the shank, a slide on the shank behind the magnet, and spring means holding the slide against the rear of the magnet to return the magnet to a forward position.

5. A magnetic attachment for can openers comprising the combination of a tool shank having a cutter at its front end, a permanent horseshoe type magnet rockably supported in a straddling position on the shank with its ends positioned at opposite sides of the cutter and movable rearwardly by contact of the magnet with a can during actuation of the cutter, means anchored to the shank and engaging the top of the magnet to hold the magnet on the shank, a slide on the shank and including forwardly projecting arms engaging the lower ends of the magnet, and spring means holding the slide forwardly and returning the lower ends of the magnet to their forward position.

6. A magnetic attachment for can openers comprising the combination of a tool shank having a cutter at its front end, a permanent horseshoe type magnet rockably supported in a straddling position on the shank with its ends positioned at opposite sides of the cutter and movable rearwardly by contact of the magnet with a can during actuation of the cutter, means anchored to the shank and engaging the top of the magnet to hold the magnet on the shank, a slide on the shank and including forwardly projecting arms engaging the lower ends of the magnet, opposed lugs on the arms engaging the inner edges of the lower ends of the magnet to hold the magnet from lateral swinging movement, and spring means holding the slide forwardly and returning the lower ends of the magnet to their forward position.
